UNITED STATES PATENT OFFICE.

EMIL F. HOLINGER, OF MCKEESPORT, PENNSYLVANIA, ASSIGNOR, BY MESNE ASSIGNMENTS, TO THE NATIONAL TUBE COMPANY, OF PITTSBURG, PENNSYLVANIA.

APPARATUS FOR MANUFACTURING HOLLOW PROJECTILES.

SPECIFICATION forming part of Letters Patent No. 638,807, dated December 12, 1899.

Application filed February 21, 1899. Serial No. 706,366. (No model.)

To all whom it may concern:

Be it known that I, EMIL F. HOLINGER, of McKeesport, Pennsylvania, have invented certain Improvements in the Art of Manufacturing Hollow Projectiles, of which the following is a specification.

These improvements relate to the art of manufacturing hollow projectiles from solid billets of metal by the employment of a die 10 for imparting the exterior form to the metal and a piercing-punch for piercing the solid billet to the required depth.

The characteristic features of the present invention are as follows: The piercing-punch is 15 stationary and occupies a vertical position, with its pointed head uppermost. The solid billet has formed in its lower end a recess conforming to the shape of the conoidal head of the piercing-punch. The die is the active member 20 of the piercing-couple and is reciprocated in a vertical path by means of suitably-arranged hydraulic pistons acting on the carriage in which the die is mounted. Vertical rods secured to the die-carriage extend down a sufficient distance below the lower end of the die 25 and are affixed to a cross-head, which is perforated to admit a vertical post, in the upper end of which the lower end of the piercing-punch is secured. A sleeve loosely applied 30 to the punch rests at its lower end upon the top of the said post, and at its upper end affords an annular bearing for the lower end of the billet. The billet may be of the same diameter as the cylindrical part of the die or 35 it may be slightly smaller in diameter than the die, in which case it will be made longer than when it is of the same diameter, if it be desired that the quantity of metal in the two forms of billet shall be the same. The upper 40 end of the die is of a hollow conoidal shape and in the center is provided with a vertical perforation of comparatively small diameter.

Apparatus suitable for carrying the invention into effect is illustrated in the accompanying drawings, which are as follows:

Figure 1 is an elevation, partly broken out and partly in vertical section, showing the billet deposited upon the upper end of the punch and supporting-sleeve and showing 50 the die-carriage supported upon hydraulic pis-

tons beneath it and also showing the ram by which the die is forced downward and showing the lower end of the hydraulic piston with which the ram is connected. Fig. 2 represents the same parts at an intermediate stage 5 in the operation at which the billet is partially pierced and its upper end partially reduced to conoidal shape. Fig. 3 represents the same parts at the concluding stage in the operation, showing the completion of the 60 piercing operation and the transformation of the upper end of the billet into the shape of the upper end of the hollow die. In Fig. 4 the die is represented in its highest position and the finished projectile as having been so 65 far elevated as to be stripped from the punch. Fig. 5 is a central longitudinal section of a billet of uniform diameter centrally recessed at one end to fit the upper end of the punch. Fig. 6 is a central longitudinal section of a 70 billet somewhat longer than the one shown in Fig. 5 and also smaller in diameter, excepting at its lower end, which is represented as having been slightly expanded during the operation of forming in it the recess to fit the 75 upper end of the punch. Fig. 7 is a central longitudinal section of the completed shell of the projectile.

In the apparatus represented in the drawings there is contained, as shown, a hollow 80 die A, interiorly shaped to conform to the cylindrical surface and conoidally-pointed head of a projectile. By means of the flange A' the die is seated in the reciprocable carriage B. The upper end of the die is provided with 85 a central longitudinal perforation A², which serves as a vent-hole for the escape of air and for the reception of any excess of metal from the upper end of the die during the concluding part of the piercing operation. The carriage is provided with vertical ribs B' B', in which there are formed perforations B² B², adapted to slide upon the columns B³ B³, the lower ends of which are fastened to the bed-plate B⁴, while their upper ends are fastened 90 to and support the main hydraulic cylinder C. The main hydraulic piston C' is provided at its lower end with the cross-head C², adapted to slide upon the vertical columns B³ B³. Affixed to and projecting downwardly from 100

- the said cross-head is the ram C³, the lower end of which bears directly upon the top of the die A. The carriage B is also provided with laterally-projecting lugs D D, adapted 5 to bear upon the upper ends of the vertical hydraulic pistons D' D', seated in the hydraulic cylinders D² D². It will be understood that the hydraulic appliances are represented conventionally.
- 10 Water under pressure is introduced into the lower ends of the cylinders D² D² when it is desired to elevate the carriage B and die A. When it is desired to force the carriage and die downward, water under pressure is 15 introduced into the main hydraulic cylinder C, and at the same time the water is allowed to escape from the lower ends of the cylinders D² D². As the carriage descends the lower open end of the die A encounters and incloses 20 the upper end of the billet E. The lower end of the billet is provided with the conoidal recess E' and is seated upon the apex or so-called "piercing-head" F of the stationary punch F'. As an additional means of appropriately 25 supporting the billet the punch is provided with the loose sleeve F², which rests at its lower end upon the top of the post F³, in which the lower end of the punch F' is secured. A cross-head G, connected by means 30 of vertical bolts G' G' to the carriage B, is vertically perforated to loosely admit the punch F' and its supporting-post F³ and constitutes the stripper for stripping the product from the punch.
- 35 The billet may be a cylinder of substantially the same diameter as the cylindrical part of the die, as represented in central longitudinal section in Fig. 5, or the same quantity of metal may be disposed in the form of 40 the billet represented in central longitudinal section in Fig. 6, the cylindrical part of which is of slightly smaller diameter than the die, except at its lower end, where the metal is represented as having been slightly expanded as 45 the result of formation in it of the recess E'.
- The finished product is represented in central longitudinal section in Fig. 7.
- As the die descends and the upper end of the billet encounters the contracted upper 50 end of the die the billet is forced downward over the punch. The displaced metal completely fills the space between the punch and the wall of the die and to some extent exudes in a downward direction around the punch.
- 55 As will be seen, the direction of motion of the die is the same as the direction of the thus exuding metal, and there is hence but little friction of the metal of the billet upon the wall of the die.
- 60 Fig. 2 illustrates the intermediate stage in

the process, at which the upper end of the billet has partially conformed to the conoidal shape of the upper end of the die and a considerable portion of the lower part of the billet has been transformed into a hollow cylindrical shape. 65

At the concluding stage of the process, as represented in Fig. 3, the die has so far descended that the lower annular end of the billet has been brought to rest by collision with 70 the upper end of the sleeve F², while the upper end of the die has been completely filled with the metal and the slight excess of metal has entered the lower end of the vent-hole A² and formed the central seat E² upon the conoidal upper end of the projectile. 75

The product contracts in cooling, so that it remains adherent to the punch, as represented in Fig. 4, until stripped therefrom by the elevation of the stripper G and the consequent 80 elevation of the sleeve F² to the position in which the parts are represented in Fig. 4.

What is claimed as the invention is—

1. In apparatus for transforming suitably heated solid metallic billets into hollow objects; a stationary vertical piercing-punch; a hollow die interiorly shaped to correspond with the exterior surface of the desired product; a movable carriage adapted to carry said die; vertical guides for guiding said carriage in a path appropriately related to the longitudinal axis of said punch; means for forcibly imparting reciprocating vertical movements to said carriage in a path extending above and below the level of the upper extremity of said stationary punch and means for supporting the object to be pierced upon the apex of the piercing-punch while the matrix is in its elevated position. 95

2. In apparatus for transforming suitably heated solid metallic billets into shells for projectiles, a stationary vertical piercing-punch; a hollow die interiorly shaped to correspond with the exterior surface and conoidally-pointed apex of the desired product; a reciprocable carriage mounted on vertical guides and adapted to carry said die in appropriate vertical alignment with said punch; means for forcibly imparting to said carriage a prescribed range of downward movement; means for elevating said carriage a suitable distance above the upper end of said punch, and a reciprocatable stripper arranged at an appropriate distance below said carriage for stripping the pierced billet from the punch. 100 105
